Primary Examiner — Brett Miller*Assistant Examiner* — Landon Thomas Cassell(74) *Attorney, Agent, or Firm* — Sughrue Mion, PLLC(57) **CLAIM**

The ornamental design for a connector, as shown and described.

DESCRIPTION

FIG. 1 is a left side perspective view from the front of a first embodiment of a connector that is the subject of the invention;

FIG. 2 is a right side elevational view thereof;

FIG. 3 is a rear view thereof;

FIG. 4 is a top view thereof;

FIG. 5 is a left side perspective view from the bottom thereof;

FIG. 6 is a front view thereof;

FIG. 7 is a bottom view thereof;

FIG. 8 is a left side elevational view thereof;

FIG. 9 is a right side elevational view of a second embodiment of a connector that is the subject of the invention;

FIG. 10 is a bottom view thereof;

FIG. 11 is a left side perspective view from the bottom thereof;

FIG. 12 is a rear view thereof;

FIG. 13 is a left side elevational view thereof;

FIG. 14 is a front view thereof;

FIG. 15 is a left side perspective view from the front thereof; and,

FIG. 16 is a top view thereof.
